UNITED STATES PATENT OFFICE

148,178

DESIGN FOR A SET OF CHESSMEN

Frank D. McNaughton, Los Angeles, Calif.

Application April 22, 1946, Serial No. 128,853

Term of patent 14 years

(Cl. D34—5)

To all whom it may concern:

Be it known that I, Frank D. McNaughton, a citizen of the United States, residing at Los Angeles, in the county of Los Angeles and State of California, have invented a new, original, and ornamental Design for a Set of Chessmen, of which the following is a specification, reference being had to the accompanying drawing, forming part thereof, and wherein:

Figure 1 is a plan view of a set of chessmen embodying my new design;

Figure 2 is an elevational view of the chessmen shown in Fig. 1; and

Figure 3 is another elevational view showing the knight and bishop turned through 90° from their positions as shown in Fig. 2; the remaining chessmen not being shown in this figure since they are symmetrical about their longitudinal axes.

I claim:

The ornamental design for a set of chessmen, substantially as shown and described.

FRANK D. McNAUGHTON.
